APPARATUS FOR HANDLING MOLTEN MAGNESIUM AND ITS ALLOYS

Clarence A. Pippin, Midland, Mich., assignor to
The Dow Chemical Company, Midland, Mich.,
a corporation of Delaware

Application October 11, 1947, Serial No. 779,333

3 Claims. (CL. 103—87)

1

The invention relates to apparatus for handling molten magnesium and its alloys and is particularly useful in the foundry for transferring the molten metal from a body thereof in a melting vessel, for example, to another location, such as a casting mold. It more particularly concerns an apparatus comprising a pump and associated parts in a combination which is especially useful as a portable device for transferring the molten metal from a melting furnace, pot, or the like, without withdrawing contaminants from the melt along with the withdrawn metal.

The ease with which molten magnesium and its alloys are attacked by the atmosphere is well known and special measures must be taken to protect the molten metal during the conventional operations with these metals such as those in the foundry. The usual method of protecting the molten metal in a melting vessel, or the like, is to cover the exposed surface with a suitable flux, such as magnesium chloride mixed with an alkali metal chloride. The presence of the flux as well as dross formation, which occurs in spite of the usual precautions to prevent atmosphere attack on the metal, makes it difficult, if not impossible at times, to withdraw and transfer clean metal from a fluxed body thereof to another location as a mold.

Heretofore molten magnesium and its alloys have been handled and transferred generally in batches carried in crucibles or ladles. Attempts to pump the molten metal as a means of transferring it from place to place, as in foundry operations, have not been wholly satisfactory with available pumping apparatus. This I have found causes contaminants to be dispersed in the melt and also entrainment of contaminants in the metal being transferred.

The principal object of the present invention is to provide an apparatus of the type indicated but which does not cause contamination of the metal and can be operated easily to transfer molten metal from place to place without entraining therein contaminants. Other objects and advantages will appear from the following description of the invention taken with the accompanying drawing.

In the drawing, the single figure is an elevation, largely in cross section, of a preferred form of the apparatus.

Referring to the drawing in detail, the apparatus of the invention, designated generally by numeral 1, is shown suspended from a hook 2 in a melt 3 contained in the melting pot 4. The melting pot 4 is supported in the furnace setting 5

2

5 and heated by the burner 6. The pot, furnace setting, and burner are conventional and not a part of the invention. As shown, the apparatus comprises a centrifugal pump, designated generally by numeral 7, built in the lower portion of the apparatus. The pump 7 consists of a rotor, having vanes 8 mounted upon the plate 9, which is secured to the lower end of the drive shaft 10 and operates within a housing. This 10 consists of a cylindrical casing 11 covered at the upper end with the plate 12 and at the lower end with the plate 13. The upper plate 12 has an opening 14 in which is secured the bushing 15 which forms the bearing for the lower end 15 of the drive shaft 10. The lower plate 13 is provided with a central opening 16 which serves as the inlet to the pump. The pump has a discharge outlet 17 in the wall of the casing 11.

The drive shaft 10, which extends upwardly 20 well above the depth of molten metal in which the pump is to operate, is surrounded in part by a shroud 18. As shown, the shroud 18 is a tubular member which extends nearly the full length of the shaft 10. The lower end of the shroud is secured, as by welding, to the upper end 25 of the pump casing 11 and preferably forms a continuation thereof.

A hood 19, preferably of conical shape, has its upper edge 20 secured to the shroud 18, its lower edge or periphery 21 preferably approximately on a level with the pump inlet 16 and has a diameter preferably between about 3 and 5 times that of the pump rotor. The under surface 22 of the hood, which slopes upwardly from the periphery, makes an angle, α , with the horizontal of not less than about 5°. A preferable angle is about 45° to 60°.

The shroud 18 just above the upper plate 12 is provided with an opening 23 which permits 40 molten metal to enter the shroud when the apparatus is immersed in the melt and to drain when the apparatus is removed from the melt.

Another opening, 24, is provided in the shroud just under the top of the hood, if the under side 45 is steeply sloping, for permitting the passage into the shroud of any gas that may be trapped in the space 25 under the hood when the apparatus is lowered into the melt.

An opening 26 in the shroud above the molten metal level is connected to a source (not shown) 50 of inert gas such as argon or helium by a pipe 27. A vent 28 closable by valve 29 is provided in the shroud.

On the upper end 30 of the shroud, there is

secured the cover plate 31 having an opening 32 slightly larger than the upper end of the drive shaft 10 which extends through the opening. The cover plate 31 carries the thrust bearing 33 which is secured to the shaft and carries the weight of the shaft 10 and pump rotor (assembly of plate 9 and vanes 8).

The driving motor 34, which is preferably compressed air driven, is mounted upon the cover plate 31 by means of the brackets 35 and coupled to the drive shaft 10 by means of the flexible coupling 36.

A ball 37 is secured to the brackets 35 and carries a ring 38 by which the apparatus may be suspended from the hook 2.

A delivery pipe 39 is connected to the discharge outlet 41 of the pump and has its upper portion 40 held by a bracket 41 mounted on the cover plate 31. Any suitable form of delivery outlet for the pipe may be provided, for example the outlet 42, which is arranged to discharge molten metal into the mold 43, for example, placed beneath the outlet.

The lower bearing 15 advantageously may be made of cast iron while other parts of the apparatus which come in contact with the molten metal may be made preferably of mild steel, although some other metals may be used if desired.

In operation, the apparatus is introduced into the body of the melt to be transferred, while inert gas is supplied to the shroud and the valve 29 is open to vent the shroud and permit displacement of air therefrom by the inert gas and molten metal which enters through ports 23 and 24. In introducing the apparatus into the melt, the flux on the surface of the melt is first parted (as in conventional ladling practice) so as to expose as clean a surface of metal as possible through which to pass the pump and hood 19, thereby to avoid flux contamination of the pump, shroud, and under surface 22 of the hood.

The apparatus is suspended from the hook 2, as exemplified in the drawing, in the melt at a level where the pump inlet 16 is well above the top of the body of settled sludge 44. After the air in the shroud has been replaced by the inert gas and molten metal, the valve 29 is closed. During operation, some inert gas may escape through the opening 32 and thrust bearing 33 unless this is gas tight. However, complete exclusion of the air from the shroud is readily accomplished in spite of such leakage by providing a constant flow of inert gas into the shroud.

The motor 34 is operated so as to turn the rotor assembly at a speed to suit the rate of metal flow desired from the outlet 40. I have found, for example, that with a rotor 7 1/2 inches in diameter having four equally spaced vanes 3/4 inch wide revolving at about 250 R. P. M. in a housing, clearing the rotor by 5/16 inch, about 40 pounds of molten magnesium or magnesium-base alloy is pumped per minute against heads of a few feet through a 3/4 inch delivery pipe.

The length of the drive shaft 10 should be sufficient to permit the motor 34 to be mounted well above the molten metal body so that reasonably cool operation of the motor is had. I have found that by using a compressed air driven motor, it may be operated satisfactorily about 1.5 to 2 feet or more above the top of the melt without overheating. Since the usual depth of the molten metal maintained in conventional melting practice does not exceed about 2 to 4 feet, the drive shaft need not be over about 4 to 6 feet long.

With the parts of the apparatus arranged and operated as described, the inert atmosphere around the drive shaft above the surface of the melt prevents atmospheric attack on the metal. Also, the shroud prevents not only the flux 45, normally used on the surface of the metal outside the shroud, but also the ambient atmosphere, from reaching the molten metal where the drive shaft penetrates the surface of the melt at 46. As a consequence, the revolving drive shaft operates the pump only in clean molten metal free from flux and products of oxidation of the molten metal. Therefore, flux and products of oxidation are not dispersed in the melt as a result of operating the pump. Furthermore, as the molten metal has free access to the interior of the shroud through the openings 23 and 24 therein, the bushing 16 is always submerged in molten metal which acts as a seal for the drive shaft obviating the need for a stuffing box on the drive shaft entering the pump housing.

In addition, the conventional foundry fluxes, as is well known, creep over the surface of the ferrous metals usually used for the construction of ladling apparatus and conventional pumping apparatus. With the present apparatus, the hood on the shroud substantially obviates flux contamination due to creeping of flux, for any flux which may creep down the outside of the shroud and hood from the surface of the melt is deterred from ever reaching the pump inlet because the flux does not creep upwardly along the upwardly sloping underside of the hood.

Among the advantages of the invention are that molten magnesium and its alloys may be safely transferred from a fluxed body thereof without withdrawing flux or other contaminants with the withdrawn metal; the rate of withdrawal is easily regulated from a small to a great rate or maintained constant, as desired; a much larger volume of molten metal can be transferred in a given time without contamination that is possible with conventional methods and apparatus.

I claim:

1. An apparatus for transferring molten magnesium and alloys thereof from a flux covered melt thereof which comprises a centrifugal pump having its rotor horizontally disposed and its inlet on the lower side; a drive shaft having its lower end secured to the rotor and of sufficient length for the upper end to extend above the surface of the melt; a shroud for the drive shaft extending from the pump to near the upper end of the drive shaft; a cover plate on the upper end of the shroud having an opening therein through which extends the drive shaft; a thrust bearing for the upper end of the drive shaft carried by the cover plate, said bearing being adapted to carry the thrust of the shaft; a bearing for the lower end of the drive shaft in the lower end of the shroud above the pump; a motor secured to the cover plate and coupled to the drive shaft for driving the same; a hood for the pump surrounding the shroud, said hood having its under surface sloping upwardly from the periphery toward the shroud and its periphery extending outwardly from the pump, said shroud having an opening under the hood communicating between the inside and outside of the shroud, and said shroud being adapted, when the hood is immersed in the melt, to maintain an inert atmosphere around the shaft above the melt and prevent flux from reaching the surface of the melt in contact with the shaft.

2. An apparatus for transferring molten magnesium and alloys thereof from a flux covered melt thereof which comprises a centrifugal pump having its rotor horizontally disposed and its inlet on the lower side; a drive shaft having its lower end secured to the rotor and of sufficient length for the upper end to extend above the surface of the melt; a shroud for the drive shaft extending from the pump to near the upper end of the drive shaft; a cover plate on the upper end of the shroud having an opening therein through which extends the drive shaft; a thrust bearing for the upper end of the drive shaft carried by the cover plate, said bearing being adapted to carry the thrust of the shaft; a bearing for the lower end of the drive shaft in the lower end of the shroud above the pump; a motor secured to the cover plate and coupled to the drive shaft for driving the same; a hood for the pump surrounding the shroud, said hood having its under surface sloping upwardly from the periphery toward the shroud and its periphery extending outwardly from the pump; said shroud having an opening under the hood communicating between the inside and outside of the shroud, and said shroud being adapted when the hood is immersed in the melt to maintain an inert atmosphere around the shaft above the melt and prevent flux from reaching the surface of the melt in contact with the shaft; and a pipe connection on the shroud for admission of inert gas thereto.

3. An apparatus for transferring molten magnesium and alloys thereof from a flux covered melt thereof which comprises a centrifugal pump

having its rotor horizontally disposed and its inlet on the lower side; a drive shaft having its lower end secured to the rotor and of sufficient length for the upper end to extend above the surface of the melt; a shroud for the drive shaft extending from the pump to near the upper end of the drive shaft; a cover plate on the upper end of the shroud having an opening therein through which extends the drive shaft; a thrust bearing carried by the cover plate for the upper end of the drive shaft, said bearing being adapted to carry the thrust of the shaft; a bearing for the lower end of the drive shaft in the lower end of the shroud above the pump; a motor secured to the cover plate and coupled to the drive shaft for driving the same; a hood for the pump surrounding the shroud, said hood having its under surface sloping upwardly from the periphery toward the shroud and its periphery extending outwardly from the pump; said shroud having an opening under the hood communicating between the inside and outside of the shroud, and said shroud being adapted, when the hood is immersed in the melt, to maintain an inert atmosphere around the shaft above the melt and prevent flux from reaching the surface of the melt in contact with the shaft; a pipe connection on the shroud for admission of inert gas thereto; and a valved vent on the shroud adapted to be opened or closed by a valve.
